Primary Examiner — Michelle E. Wilson*Assistant Examiner* — Rochel L Rimelspanch-Zare(74) Attorney, Agent, or Firm — INNOVATION CAPITAL LAW GROUP, LLP; Vic Lin(57) CLAIM

The ornamental design for a beer pong game as shown and described.

DESCRIPTION

FIG. 1 is a perspective view of a beer pong game, showing our new design;

FIG. 2 is a front elevation view thereof;

FIG. 3 is a rear elevation view thereof;

FIG. 4 is a left side elevation view thereof, the right side of which is a mirror image;

FIG. 5 is a top plan view thereof; and,

FIG. 6 is a bottom plan view thereof.

The broken lines depict portions of the beer pong game that form no part of the claimed design.
